United States Patent Office

Des. 192,451

Patented Mar. 20, 1962

192,451

JUG

Theodore Kaplan, 21 Ivanhoe St., Newton, Mass.

Filed Mar. 16, 1961, Ser. No. 64,324

Term of patent 14 years

(Cl. D58—5)

Fig. 1.

Fig. 2.

Fig. 3.

FIG. 1 is a side elevation of a jug showing my new design.

FIG. 2 is a rear elevation of the same.

FIG. 3 is a top plan view of the same.

The decorative rib at the top extends around three sides of the jug, the rib at the bottom extends around all four sides, and the bottom is rectangular with rounded corners.

I claim:

The ornamental design for a jug, as shown and described.
